LLP(57) **CLAIM**

The ornamental design for a coaxial connector, as shown and described.

DESCRIPTION

FIG. 1 is a perspective view of a coaxial connector in a closed position, showing my new design;
 FIG. 2 is a front elevation view thereof, the rear, left side and right side elevation views are mirror images thereto;
 FIG. 3 is a top plan view thereof; and,
 FIG. 4 is a bottom plan view thereof.

The broken lines in the drawings depict environmental structure, are for illustrative purposes only and form no part of the claimed design.
